UNITED STATES PATENT OFFICE.

JOHN W. BARTLETT, OF MOLINE, ILLINOIS, ASSIGNOR TO THE MOLINE PLOW COMPANY, OF SAME PLACE.

CHECK-ROW DEVICE FOR PLANTERS.

SPECIFICATION forming part of Letters Patent No. 398,485, dated February 26, 1889.

Application filed June 8, 1888. Serial No. 276,514. (No model.)

To all whom it may concern:

Be it known that I, JOHN W. BARTLETT, of Moline, in the county of Rock Island and State of Illinois, have invented certain Improvements in Check-Row Devices for Seeders, of which the following is a specification.

At the present day it is a common practice to operate the seed-dropping mechanism of corn-planters by means of knotted wires or cords stretched across the field from side to side and attached to anchors at their ends, these wires being commonly known as "check-rowing" wires. In the use of these wires it is the custom to drive the machine across the field under the wire in one path and to return the machine in a different path parallel with the first, after which the wire is shifted laterally at the points of commencement. As the machine completes its return movement in the new path it causes the wire or cord to be strained laterally in relation to the anchor.

It is the aim of my invention to provide an anchor by which the wire or cord may be held rigidly in position until the planter in its return movement is brought near to or abreast of the anchor, and which will then automatically unlock the end of the wire and retain the same with a yielding strain, so that the planter may continue its course to the extreme edge of the field. To this end I provide an anchoring device having a blade to enter the ground, a spring-actuated drum or take-up with a cord for attachment to the check-rowing wire, and an automatic latch by which the cord is rigidly held independently of the winding-drum and prevented from unwinding until the wire is urged laterally by the approaching planter.

In the accompanying drawings, Figure 1 is a perspective view of my anchor as it appears with the wire-holding arm unhooked. Fig. 2 is a vertical central section through the same. Fig. 3 is a horizontal section on the line $x-x$ of Fig. 1. Fig. 4 is a vertical section through the lower part of the case on the line $y-y$. Fig. 5 is a side elevation of my anchor with the side of the casing removed to show the internal winding-spring.

Referring to the drawings, A represents a flat circular body recessed in its two sides,

provided at its top with a socket, a' , to receive the wooden staff or handle a^2 , and provided at its lower side with a projection, a^3 , recessed to receive the upper end of a flat blade, B, which is secured firmly therein by a bolt, b , 55 or equivalent fastening device. The projection at the lower side of the case is provided on one side with a stop or foot piece, a^4 , by means of which the operator is enabled to force the blade deeply and firmly into the ground in order to fix the anchor in position.

The blade is constructed of a flat or angular form in cross-section, in order to prevent its rotation in the ground and to hold the device against turning when subjected to side strain, as hereinafter explained. While I prefer a flat blade, such as represented in the drawings, it may be modified in cross-section, provided only its form is such as to arrest the turning motion in the ground. 70

The two recessed sides of the case are covered by flanged side plates, a^5 . Through the center of the case there is passed a shaft, C, the ends of which are reduced and formed with journals bearing on the side plates, which latter are held in place by pins c , passed through these journals. 75

A strong coiled spring, D, is seated in one side of the case or body and secured at one extremity thereto, and at the opposite or inner extremity secured to the central shaft, C. In the other side of the case is located a wheel or drum, E, keyed or otherwise securely fastened to the shaft and provided with a peripheral groove. A cord, F, is wound within 85 the periphery of the pulley and fixed at one end thereto, its opposite end being passed outward through a hole in the lower side of the case and permanently attached to an arm or latch, G. The spring, being under tension, 90 acts through the shaft to turn the pulley and keep the cord wound normally thereon, so that the arm G can be drawn from the case only by the application of considerable power.

The case or body is provided at its lower side with a rigid horizontal arm or extension, a^6 , having on its side face a stud, a^7 , designed to enter a hole, g , in the arm G, for the purpose of establishing a rigid connection between the arm and the anchor proper. A 100

spring, H, secured to the case or body, stands at its free end opposite the stud a^7 , for the purpose of holding the arm G in engagement therewith. When, however, a lateral strain 5 is applied to the outer end of the arm G, the spring will yield and permit its disengagement.

The operation of the anchor is as follows: The arm G is first engaged upon the stud a^7 , 10 as shown in Fig. 3. The planter being at one side of the field, the anchor is set in line directly behind its check-rowing mechanism and the operating cord or wire attached to the end of the arm or latch G. The planter is 15 then driven across the field and returned in a different path, as usual. During this time the arm G remains in rigid connection with the anchor until the planter closely approaches the anchor in its return movement, whereupon the 20 wire, being drawn laterally by the planter, causes the arm G to tip sidewise and disengage from the stud a^7 . The movement of the planter is continued until it stands opposite the side of or is carried past the anchor. During this 25 final movement the strain upon the arm G causes the cord F to overcome the resistance of the spring and unwind from the drum, the spring acting through the intermediate parts to maintain a yielding strain on the check-row wire. The anchor is then withdrawn from 30 the ground, either with or without disconnecting the wire from the arm G, and the operation repeated, the cord F being automatically retracted by the drum, and the arm or latch 35 G being again engaged previous to the next course of the planter.

While I have represented the preferred construction in all the details, it is to be understood that the essence of my invention 40 resides in the combination, with the anchor, of an arm or latch, G, adapted to be disengaged therefrom, and a yielding cord or winding device to hold said latch after its disengagement, and it is manifest that the details may be 45 modified within the range of mechanical skill.

It is to be noted that in my device the winding-drum and spring do not act to maintain the tension of the wire or cord or retain its 50 end until the planter has crossed the field and passed the anchor at the end of its jour-

ney. During the normal condition of the parts, and while the machine is crossing the field between the anchors, the cord is held rigidly by the latch, the spring and drum remaining inert and without effect or influence 55 on the other parts.

Having thus described my invention, what I claim is—

1. In an anchor for a check-row wire or cord, the combination of a case or body having 60 a blade to enter the ground, the winding-drum and its actuating-spring, the cord attached to and winding on the drum, and the arm or latch G, attached to said winding-cord and adapted to receive the check-row wire, 65 and also adapted to engage directly and detachably with the body.

2. In an anchor for a check-row wire, the case or body having the flat or angular blade adapted to resist rotation in the ground, the 70 stud a^7 , and spring H, and the laterally-detachable arm G, adapted to engage the stud, said elements constructed and combined, as described, to permit the lateral disengagement of the arm G.

3. In an anchor for a check-row wire, the combination of a body having the flattened or angular blade adapted to enter the ground and resist rotation therein and an arm or latch, G, to receive the check-row wire directly 80 interlocked with the body and adapted to disengage therefrom by a lateral movement.

4. The case recessed in its two sides and provided with an anchoring blade and handle, in combination with the central shaft, the 85 spring, the drum or pulley, the cord winding on the drum, and the arm or latch attached to said cord.

5. The case recessed in its two sides, the side plates applied thereto, and the central 90 shaft provided with the plate-holding pins, in combination with the spring, pulley, and cord, as shown.

In testimony whereof I hereunto set my hand, this 16th day of May, 1888, in the presence of two attesting witnesses.

JOHN W. BARTLETT.
